UNITED STATES PATENT OFFICE.

JOHN E. BOSSERMAN, OF MURRAY, IOWA.

GRAIN ELEVATOR.

Application filed February 20, 1923. Serial No. 620,124.

To all whom it may concern:

Be it known that I, JOHN E. BOSSERMAN, a citizen of the United States, and a resident of Murray, in the county of Clarke, State of Iowa, have invented a certain new and useful Grain Elevator, of which the following is a specification.

This invention relates to mechanism for conveying and discharging grain from the 10 delivery spout of a grain elevator to the inside and ends of cars.

Heretofore it has been the practice to deliver the grain through the grain door of the car on the car floor and just inside of the 15 door, and to shovel it back into the car by manual labor. On account of the amount of labor involved and the dust conditions it is almost impossible to get men to do this work.

20 It is, therefore, the object of my invention to provide a mechanism of simple, durable, inexpensive and light construction which may be easily and quickly attached to the upper edge of one of the car doors, and 25 which will automatically deliver the grain from the delivery chute of the elevator to either end of the car.

More specifically it is the object of my invention to provide a conveying or delivering 30 mechanism for the purpose above stated, which may be constructed in sections and so arranged that the said sections may be easily assembled or taken apart so that the machine may be easily handled and moved from one 35 car to another.

My invention consists in the construction, arrangement and combination of the various parts of the device, whereby the objects contemplated are attained, as hereinafter more 40 fully set forth, pointed out in my claims, and illustrated in the accompanying drawings, in which:

Figure 1 is a side elevation of my improved device showing the manner in which 45 it is mounted on a grain door of a car.

Figure 2 is a horizontal, sectional view taken through a car showing in elevation my improved mechanism and the manner in which it is mounted therein.

50 Figure 3 is an enlarged, detail, sectional view showing one of the pivoted members on which the conveyor is mounted.

Figure 4 is an end elevation of my improved device.

55 The numeral 10 indicates the sides and 11 the bottom of a grain car. The sides 10

are provided with door openings 12, each of the openings 12 being provided with the usual grain doors 13. The grain doors 13 consist simply of a series of horizontally arranged boards nailed to the inner edge of the door frames 14. The boards of the grain doors are nailed to the said door frames and usually extend about four feet high, the grain door being about eight feet 65 high, which would leave the upper edge of the door 13 midway between the top and bottom edges of the door opening 12.

My improved device comprises a horizontally arranged platform or base 15 which 70 is provided at each end with a bracket 16 having at one of its sides a hook 17 provided with a clamp screw 18. The hook and said screw form a clamp designed to be placed over the upper edge of the door 13 for securing the platform in a horizontal position, even with the upper edge of the door 13 and extending inwardly from said upper edge. The brackets 16 are preferably provided 75 with braces 19 to hold the platform 15 80 against longitudinal movement.

Rotatively mounted on the platform is a base member 20 pivoted to the platform by the pin 21. One end of the base is provided with upright supporting brackets 22. The 85 upper end of each of the brackets being provided with an outwardly inclined slot 23. The brackets 22 are spaced apart a short distance and designed to receive between them a conveyor box 24. The said 90 conveyor box has bearing members 25 extended laterally from each of its side members, said bearing members being designed to rest in the slots of the members 23, as clearly shown in Figure 3. This provides 95 means whereby the outer end of the conveyor box may be elevated or lowered and whereby the box may be easily and quickly detached by simply lifting it out of the inclined grooves.

100 The pivoted end of the conveyor box is provided with upwardly extending plates 26 which are designed to support a side plate 27 detachably connected thereto by means of bolts 28. The upper end of each of the plates 26 is provided with laterally extending pin 29. Each of the pins 29 is designed to receive a notched brace bar 30. The lower end of each of the brace bars is pivoted to the base 20 by brackets 31. The 110 brace bars 30 are designed to support the free end of the conveyor box 24, in a num-

ber of elevated positions so that the outer end of the conveyor box may be inclined upwardly or downwardly.

The outer end of the box 24 is provided with an extension 32 which is secured to the box by hinges 33 so arranged that the free end of the extension may be turned upwardly to a vertical position, or if desired, thrown back on top of the conveyor box 24.

10 The outer end of the extension member 32 is provided with a shaft 34 designed to receive a pulley 35, while the bearings 25 are designed to receive a transversely arranged shaft 36 on which is supported a pulley 37.

15 The pulleys 35 and 37 are designed to carry a conveyor belt 38. The upper run of the said belt is designed to travel over a floor board 39 in the box member 24, and a floor board 40 in the extension 32. The adjacent ends of the boards 39 and 40 are cut away to form a notch 41 between them. The said notch is for the purpose of permitting the free end of the extension 32 to swing upwardly, while the belts are in position on the rollers, without stretching the said belt.

20 One end of the shaft 36 is provided with a pulley wheel 42 designed to receive a belt 43 operated from an electric motor 44, the said motor being placed on the base 20 at the opposite end from the uprights 22.

25 Thus it will be seen that if the motor 44 is operated, the shaft 36 will be rotated through the belt 43 and the pulley 42. This will cause the conveyor 38 to be rotated in an anti-clockwise direction, as shown in Figures 1 and 2 and any material which is delivered to the conveyor through a chute 45 will be carried outwardly to the end of the conveyor 38 and discharged.

30 The platform 15 is placed on the upper edge of the door 13, as clearly shown in Figures 1 and 2 and the clamps 17 over the upper edge of the said door. It will be seen that the platform may be slid longitudinally along the upper edge of the door and a certain amount of adjustment made between the outer end of the conveyor and the end of the car.

35 It will further be seen that the free end of the conveyor may be swung laterally so that the material may be discharged midway between the sides of the car.

40 After one end of the car has been filled and it is desired to fill the other end, the operator simply swings the free end of the extension member 32 upwardly about the hinge 33, which will then permit the conveyor to swing about the pivot 21 and between the sides of the car until it has reached the position where it will be in alignment with the opposite end of the car. The extension 32 may then be lowered and the side plate 27 adjusted to the opposite side of the conveyor and the chute replaced,

45 after which the mechanism is again ready for operation. The outer end of the conveyor is adjusted to various elevations by simply unhooking the braces 30, and then moving the outer end of the conveyor member 24 upwardly or downwardly to the desired position, and then again placing the hooks of the member 30 over the pins 29.

50 When it is desired to remove the conveyor from the car, the extension 32 is thrown upwardly and inwardly to a position over the top of the conveyor 24, after which the braces 30 are unhooked from the pins 29 and the belt 43 removed, which will leave the pivot end of the conveyor free to be disengaged from the supports 22 by lifting upwardly and inwardly. The conveyor 24 is removed through the car door opening, and is comparatively light and may be easily handled by one man. The platform 15 may then be removed, which is also very light, due to the fact that a very small motor is required to operate the mechanism.

55 Thus it will be seen that I have provided a device of simple, durable and inexpensive construction which is adapted to deliver grain or the like to the ends of grain cars, and which may be easily and quickly placed in position for operation, or quickly and easily removed by a single operator without the use of tools.

60 I claim as my invention:

1. In a device of the class described, a platform having brackets attached to its lower side, said brackets being provided with clamps, said clamps being designed to clamp on the upper edge of one of the grain doors and hold the platform in a horizontal position, a base member pivotally mounted on said platform, a motor on said base, a conveyor having one end attached to said base member, and means for driving said conveyor from said motor.

65 2. In a device of the class described, a platform, means for detachably securing the platform in a horizontal position to the upper edge of a car door, a base pivotally mounted on the upper face of said platform, a conveyor box having one end pivoted to said base member, an extension member pivoted to the outer end of the conveyor box, a conveyor for said box and said extension, and means for driving said conveyor.

70 3. In a device of the class described, a platform having brackets attached to its lower side, said brackets being provided with clamps, said clamps being designed to clamp on the upper edge of a grain door, and hold the platform in a horizontal position, a base member pivotally mounted on said platform, a motor on said base, a conveyor having one end pivotally and detachably secured to said base member, means for driving said conveyor from said motor, and

a pair of arms each having one of their ends hinged to the base member and their free ends provided with a series of notches designed to receive a lug provided on each side of the pivoted end of the conveyor, for the purposes stated.

4. In a device of the class described, a platform having brackets attached to its lower side, said brackets being provided with clamps, said clamps being designed to clamp

on the upper edge of a grain door, and hold the platform in a horizontal position, a base member pivotally mounted on said platform, a motor on said base, a conveyor having one end pivotally and detachably secured to said base member, means for driving said conveyor from said motor.

Des Moines, Iowa, January 31, 1923.

JOHN E. BOSSERMAN.
